UNITED STATES PATENT OFFICE.

JOHN MURPHY, OF PARSONS, KANSAS.

JOINTED PISTON-HEAD PACKING-RING.

SPECIFICATION forming part of Letters Patent No. 768,136, dated August 23, 1904.

Application filed May 11, 1903. Serial No. 156,546. (No model.)

To all whom it may concern:

Be it known that I, JOHN MURPHY, a citizen of the United States, residing at Parsons, in the county of Labette and State of Kansas, have invented new and useful Improvements in Jointed Piston-Head Packing-Rings, of which the following is a specification.

My invention relates to packings for piston-heads of steam-engine cylinders; and my invention consists in the combination of three or more packing-segments with an interior spring which presses outwardly against the segments.

The advantages of my herein-described packing over the usual one-piece packing-rings are: With my packing the pressure of the packing upon the cylinder is much less. With my packing the pressure of the packing upon the cylinder is equal at all points of its periphery, and hence neither the packing nor the cylinder will be unequally worn away by the reciprocation of the piston, which unequal wear is a serious fault of the old-style one-piece packing-rings.

My invention possesses further advantages, which it is not necessary to explain.

My invention is completely illustrated in the accompanying drawings, in which—

Figure 1 is an elevation of a packing-ring embodying my invention. Fig. 2 is an edge view of the same. Fig. 3 is a sectional view of a part of a piston-head provided with my packing. Fig. 4 represents the ends of the packing-spring, the adjacent portion of the bull-ring, and a pin projecting from the latter between the ends of the spring.

1 designates the packing-ring, which is turned from cast-iron or other metal to the same diameter as the bore of the cylinder for which it is intended. Then said ring is sawed into three or more equal segments 1 1 and 1, three being the preferred number. In the meeting ends of two of said segments I cut recesses 3, the purpose of which is to receive the ends of a spring described hereinafter. The two joints 4 are filed and scraped to true planes and are then rubbed together with

wet emery-powder between them while in the cylinder. These processes insure that the said joints between the segments will be steam-tight when the ends of the segments are in contact.

Within the packing-ring is forced a C-shaped steel spring 5. When free, the diameter of this spring is about one-quarter larger than that of the packing-ring. The ends of said spring are bent outwardly and are inserted in the recesses 3 in the ends of the packing-segments. The elasticity of said spring not only forces the segments 1 outwardly against the cylinder, but presses them together at their joints 4. Thus a small gap 6 will be left between the ends of the recessed segments. This gap is placed at the bottom of the cylinder when the bull-ring 7, Figs. 3 and 4, is in steam-tight contact with the cylinder. The packing-grooves in the bull-ring are about one-eighth inch deeper than the combined thickness of the packing-ring and its spring 5.

In Fig. 3 the packing-rings project from the piston, as the cylinder is not shown.

A pin or stud 8 is driven tightly into a hole in the face of the bull-ring 7 near its periphery, and said pin projects between the ends of the spring 5. The bull-ring being non-rotatable, pin 8 prevents the packing-ring from working around out of its proper position, as one end of the spring 5 would strike the pin and prevent such slipping. When the steam is admitted to the cylinder, it increases the pressure both on the joints and against the cylinder.

It will be evident that my packing possesses the advantages mentioned hereinbefore, and is inexpensive to construct and reliable in its operation.

A plurality of nested C-shaped springs may be substituted for the single spring 5 without departing from the spirit and scope of my invention.

Having now fully described my invention, what I claim as new, and desire to secure by Letters Patent of the United States, is—

The combination with a bull-ring, of a pack-

ing-ring comprising a plurality of segments, recesses cut in the meeting ends of two of said segments, a C-shaped spring confined within said ring, the ends of said spring being bent outwardly into said recesses, and a pin secured to the bull-ring and projecting between the ends of said spring, substantially as described.

In testimony whereof I affix my signature in the presence of two witnesses.

JOHN MURPHY.
